UNITED STATES PATENT OFFICE.

FRANK STINER, OF LAWRENCE, MASSACHUSETTS.

PNEUMATIC CLOTH-FINISHING MACHINE.

SPECIFICATION forming part of Letters Patent No. 657,300, dated September 4, 1900.

Application filed May 28, 1900. Serial No. 18,245. (No model.)

To all whom it may concern:

Be it known that I, FRANK STINER, of Lawrence, in the county of Essex and State of Massachusetts, have invented certain new and 5 useful Improvements in Pneumatic Cloth-Finishing Machines, of which the following is a specification.

This invention relates to machines for extracting water from fabrics in which the fabric 10 is spread or stretched and subjected to the action of a suction apparatus which draws the water through the back side of the fabric and carries the water away from the face or right side thereof, so that the face is prevented 15 from being clouded or streaked by the "bleeding" of the dye or coloring-matter with which the body and backing of the fabric is impregnated.

The invention has for its objects to provide 20 a machine of this character adapted to more effectively extract water in the manner described than heretofore and also to provide a machine which can be used, if desired, for applying liquid to the face side of the fabric 25 and drawing the same liquid through the fabric and from the back side, leaving the fabric slightly and uniformly dampened either as a preparation for pressing or to sponge and shrink the fabric before it is cut 30 and made up.

The invention consists in the improvements hereinafter set forth and claimed.

Of the accompanying drawings, forming a part of this specification, Figure 1 represents 35 a perspective view of a machine embodying my invention. Fig. 2 represents a longitudinal vertical section of the same. Fig. 3 represents a section on line 3 3 of Fig. 2, showing also a side elevation of the suction-pump. Fig. 4 represents an enlargement of 40 a portion of Fig. 3. Fig. 5 represents a side elevation of parts of the machine. Fig. 6 represents an elevation showing parts of the tension device shown in Fig. 2. Fig. 7 represents a section on line 7 7 of Fig. 6.

The same reference characters indicate the same parts in all the figures.

In the drawings, 1 represents the frame of the machine, which may be of any suitable 50 form and construction.

2 2 represent suction pipes or beds, of which two are shown, these being supported side by

side on the frame 1 and connected by a branched coupling-section 4 with a conduit 5, which is connected with a pump 6, adapted 55 to draw air and liquid through the suction-pipes 2 2. Said pipes have slots 7 7 in their upper portions, over which the piece of fabric 8 to be finished is drawn under tension, as hereinafter described. Above the suction-pipes 2 2 are rubber-covered rolls 9 9, which bear on the upper or face side of the piece 8 and prevent the free admission of air to the slots 7 through the intermediate fabric, the rubber coverings of the rolls being sufficiently 60 elastic to cause their under sides to flatten when they bear on the fabric, and thus obstruct the passage of air through the fabric, the rolls at the same time squeezing the water 65 from the fabric and facilitating its withdrawal 70 through the slots 7.

10 10 represent sprinkler-pipes which are located above the suction-pipes and are connected with a source of water-supply and provided with perforations arranged to deliver 75 water in numerous small streams 100 on the fabric at points close to the pipes 2 and rolls 9, the fabric being thus saturated or dampened, if desired, just before it passes over the slots of the suction-pipes. If this saturation 80 is not desired, movable troughs 12 12, supported by swinging arms 13 13, may be moved by means of a handle 14 into position to catch the water discharged by the pipes 10, said troughs being provided with flexible outlet-pipes 15, discharging into a pan 16, affixed to 85 the frame 1. Said pan is arranged to also receive any water that may fall from the external surfaces of the suction-pipes and has a waste-pipe 17. The fabric enters the machine 90 between tension-bars 18 18, which are attached to arms 19 19, having trunnions 20. Said trunnions are locked with the arms 19 at any desired angle by means of disks 21, Fig. 7, affixed to the trunnions, and frictional clamps 95 22 22, surrounding said disks and hinged at 23 to fixed arms 24 on the frame 1. A screw 25 in the outer ends of the clamps tightens the clamps on the disks 21, thus locking the arms 19 and tension-bars 18.

100 From the tension-bars the fabric passes over a guide-roll 26 and from thence downwardly to a guide-roll 27, a vertical stretch of the fabric being thus subjected to the action of a ro-

tary brush 28, which brushes the back side of the fabric. Guide-rolls 29 30 present another vertical stretch of the fabric to another rotary brush 31, which acts on the face side of the fabric. Under the brushes 28 and 31 are receptacles 32 32 for the lint, &c., removed from the fabric by the brushes. The guide-roll 30 cooperates with another guide-roll 33 in guiding a horizontal stretch of the fabric between the suction-pipes 2 2 and rolls 9 9. From the guide-roll 33 the fabric passes downwardly under a guide-roll 34 and from thence to a draft-roll 35, which has a suitably-roughened periphery and is connected with the driving-shaft 37 by means of a belt running on cone-pulleys 38 39, Fig. 1. The fabric passes from the driving-roll under a guide-roll 40 and from thence over a final guide-roll 41 either downwardly by an oscillating folder 42 or upwardly to a winding-roll or mandrel 43.

The various guide-rolls, excepting the final roll 41, are preferably adjustably mounted by means of brackets or hangers 44, attached to the frame 1 by bolts passing through slots 45 in said brackets, the latter having bearings for the journals of the guide-rolls. The brushes 28 and 31 are driven by a belt 46, Fig. 2, running on a pulley 47 on the driving-shaft and on pulleys on the brush-shafts.

The suction-pipes 2 2 are preferably provided with air-inlets 48, Fig. 3, which may be closed by valves 49, adapted to be simultaneously operated by the lever 50 and connections 51 52. (Shown in Fig. 5.) These valves may be adjusted to prevent the admission of air to the suction-pipes or to permit more or less air to enter the same, thus varying the force with which water is drawn from the fabric by the action of the pump.

The sprinkler-pipes 10 10 are connected with a water-supply pipe 54 by the branches 55 55 and the intermediate connections 56 57. (Shown in Figs. 1 and 3.) A steam-pipe 58 admits steam to the water at a point between the branches 55 55 for the purpose of heating the water, if desired.

Each suction-pipe 2 is provided with a valve or gate 59, whereby either pipe may be shut off from the pump. Valves 60 60 are provided, whereby water may be shut off from either of the sprinkler-pipes 10. Pressure-gages 61 are connected with the pipes which supply the sprinkler-pipes 10, and a pressure-gage 62 is connected with the suction-duct 5.

Each of the sprinkler-pipes 10 has a swab 63, attached to a handle 64, which is movable through a stuffing-box 65 at one end of the sprinkler-pipe. The swab is of such diameter that it closely fits the perforated portion of the sprinkler-pipe and removes any sediment which may accumulate therein, thus preventing the obstruction of the perforations.

It will be seen that the sprinkler pipe or pipes arranged to deposit water on the face side of the fabric, so that it will be drawn

through the fabric and from the back side thereof by the suction apparatus, enables the machine to be used for dampening fabric introduced in a dry condition into the machine, the water being forced into the fabric by the rubber-covered roll or rolls and drawn through the fabric and from the back side thereof by the suction apparatus. The fabric may thus be properly dampened preparatory to the pressing operation, or it may be sponged or shrunk in this way before being cut and made up. The machine may therefore be advantageously used as a sponging-machine. The sprinkler-pipe may discharge water directly on the upper surface of the roll 33, the liquid being carried by the surface of the roll to the face of the fabric.

Having thus explained the nature of my invention and described a way of constructing and using the same, although without having set forth all the forms in which it may be embodied or all the modes of its use, I declare that what I claim is—

1. A machine of the character specified comprising a pipe or chamber having a slot or opening, means for exhausting air from said pipe or chamber, means for guiding fabric in contact with said pipe or chamber and across said slot or opening, and means for pressing on the surface of the fabric adjacent to said slot or opening and on the side opposite that which bears against said pipe or chamber.

2. A machine of the character specified comprising a pipe or chamber having a slot or opening, means for exhausting air from said pipe or chamber, means for guiding fabric in contact with said pipe or chamber and across said slot or opening, means for sprinkling the fabric prior to its passage across the slot or opening of said pipe or chamber, and means for pressing on the surface of the fabric adjacent to said slot or opening and on the side opposite to that which bears against said pipe or chamber.

3. A machine of the character specified comprising a plurality of slotted suction-pipes having liquid-receiving openings, means for exhausting air from said pipes common to said pipes, rolls located adjacent to said openings, and means for guiding fabric between said suction-pipes and rolls.

4. A machine of the character specified comprising a slotted suction-pipe, means for exhausting air therefrom, an elastic pressure-roll adjacent to the slot in said pipe, and means for guiding fabric between the suction-pipe and pressure-roll.

5. A machine of the character specified comprising a plurality of pipes or chambers having slots or openings, means common to said pipes or chambers for exhausting air therefrom, valves or gates whereby either pipe may be shut out of operation, means for guiding fabric in contact with said pipes or chambers and across the slots or openings thereof, and means for pressing on the surface of the fab-

ric adjacent to said slots or openings and on the side opposite that which bears against said pipes or chambers.

6. A machine of the character specified comprising a slotted pipe, means for exhausting air therefrom, a pressure-roll located over the slot in said pipe, means for guiding fabric in contact with said pipe and across the slot, and a sprinkler-pipe arranged to deliver water on the face side of the fabric.

7. A machine of the character specified comprising a slotted suction-pipe, means for exhausting air therefrom, a pressure-roll adjacent to the slot in said pipe, means for guiding fabric between the suction-pipe and roll, a sprinkler-pipe arranged to deliver water on the fabric near the suction-pipe or roll, and a movable swab in said sprinkler-pipe.

8. An apparatus of the character specified comprising a slotted suction-pipe, means for exhausting air therefrom, a pressure-roll over the slot in said pipe, a sprinkler-pipe, means for admitting steam to the water supplied to the sprinkler-pipe, and means for guiding fabric between said suction-pipe and roll.

9. An apparatus of the character specified comprising a slotted suction-pipe, a pressure-roll adjacent to the slot in said pipe, a sprinkler-pipe, a system of piping arranged to supply the sprinkler-pipe, a steam-pipe connected with said system, means for exhausting air from said suction-pipe, and means for guiding fabric between said suction-pipe and roll.

10. An apparatus of the character specified,

comprising a suction-pipe, a roll over the said pipe, a sprinkler-pipe, and a movable intercepting-trough adapted to be moved to position to catch the water from the sprinkler-pipe.

11. An apparatus of the character specified, comprising a suction-pipe having openings, means for exhausting air therefrom, a roll adjacent to the openings in said pipe, a sprinkler-pipe, a trough under the suction-pipe and sprinkler-pipe said trough having a waste-pipe, and means for guiding fabric between said suction-pipe and roll.

12. An apparatus of the character specified, comprising a supporting-frame, an air-exhausting mechanism, a pipe or chamber having a slot or opening, means for guiding fabric in contact with said pipe or chamber and across said slot or opening, means for exhausting air from said pipe or chamber, rolls supported by the frame and arranged to hold the piece or web of fabric while being subjected to the action of the exhaust, tension-bars arranged to act upon the fabric at the receiving end of the frame, means for adjustably supporting the tension-bars, and means for locking the tension-bars in any position to which they may be adjusted.

In testimony whereof I have affixed my signature in presence of two witnesses.

FRANK STINER.
